UNITED STATES PATENT OFFICE.

WILLIAM J. HERBST, OF NEW ORLEANS, LOUISIANA.

MAIL-BAG CATCHER.

1,117,380.

Specification of Letters Patent.

Patented Nov. 17, 1914.

Application filed November 4, 1913. Serial No. 799,214.

To all whom it may concern:

Be it known that I, WILLIAM J. HERBST, a citizen of the United States, residing at the city of New Orleans, in the parish of Orleans and State of Louisiana, have invented 5 certain new and useful Improvements in Mail-Bag Catchers, of which the following is a specification.

This invention relates to a mail bag catching and delivering device.

One object is to provide catching devices, one at the station and one carried by the train, so that when the train is moving past the station a mail bag may be delivered to 15 the moving train and a mail bag delivered from the moving train to the station catching device, both mail bag catching devices being yieldably mounted and composed mainly of yieldable material so as to reduce 20 impact incident to the reception of the bags into the catching devices.

Another object resides in the provision of a mail bag catching and delivering device embodying simplicity, inexpensiveness, economy, and durability.

With the above and other objects in view, the present invention consists in the combination and arrangement of parts herein-after more fully described, illustrated in the 30 accompanying drawings and particularly pointed out in the appended claims, it being understood that changes may be made in the form, proportion, size and minor details without departing from the spirit or sacrificing any of the advantages of the invention.

In the drawings:—Figure 1 is a top plan view of the invention showing a portion of a train in horizontal section. Fig. 2 is a 40 front elevation. Fig. 3 is an enlarged detail fragmentary view illustrating the mounting for the swinging catching device carried by the train.

Referring now more particularly to the 45 accompanying drawings the reference character 10 indicates a platform arranged between or adjacent the tracks at a station. Steps 11 may lead to this platform and adjacent the same is disposed a fixed post 12 provided with upper and lower bearings 13 50 and 14 for the swinging support of a vertical bar 15. The post may be braced in any suitable manner but, as shown, it is braced by the downwardly diverging braces 12', each 55 having an eye bolt or the like 12a for a purpose presently explained.

Connected to and projecting from the swinging bar 15 are upper and lower arms 16 and 17 which are connected at their outer ends by the bar 18. These arms and said bar are preferably composed of tubular metal so as to provide for lightness, rigidity and such strength as will permit of the functions intended by the present invention. The bars 15 and 18 and the arms 16 and 17 60 provide a rectangular shaped frame. This frame is designed to support chain mesh a or other suitable material as shown for the purpose of providing a cage A to receive the mail bag 24 from a moving train as will be 65 hereinafter explained. This chain mesh a or other suitable material is preferably flexible and forms a cage with an open mouth formed by the aforesaid frame.

In the door opening 25 at the side of the 75 car 26 is mounted a cage B formed exactly the same as the cage A. The cage B is connected to a swinging rod 27 journaled in a plate 28 at the top of the door opening 25 and at its lower end journaled in a plate 29 80 on the sill of the door opening 25. This plate 29 is provided with an annular raised portion 30 having a plurality of recesses 31, there being a slot 32 formed in the plate 29 and through the raised portion 30 to permit 85 the lug 33 on the trunnion 34 of the post 27 to pass under the plate 29 and swing away from the slot 32 when the cage B is thrown outwardly to receive the mail bag 35 as will be hereinafter explained. The lower end 90 of the post or bar 27, immediately above the trunnion 34, has a plurality of lugs 36 adapted to engage in the recesses 31 to hold the post or bar 27 firmly in its outward position and yet permit an inward swinging 95 movement of the cage B into the car through the door opening 25.

The aforesaid bar 15 carries an arm 37 adjacent its lower end while the bar 27 carries an arm 38 adjacent its upper end. 100 At the outer end of the arm 37 is a clip 39 while at the outer end of the bar 38 is a clip 40.

To position the cages A and B for the purpose of taking and delivering mail bags 105 24 and 25, the cage A is thrown outwardly away from the post 12. Two springs 41 are attached to the mesh of which the cage A is formed, one at the upper rear corner and the other at the lower rear corner. These 110 springs are connected to the eye bolts 12a on the braces 12' of the post 12. The cage B

carries two springs 42 in the same way and which are preferably connected to the upper and lower eye bolts 43 on either side of the door according to the direction of movement of the train. These springs 41 and 42 serve as cushions or means for taking up shock incident to impact of the mail bags against the cages. There is a plate 44 similar in form to the plate 29 arranged at the 10 opposite side of the door opening 25 for the support of the swinging bar 27 if it be desired to reverse the position of the cage B.

When it is desired to deliver a mail bag to the station and to take a mail bag from the 15 station on to the moving train, the mail bag 24 is positioned by an attendant at the station by connecting the upper end of the mail bag 35 by the flexible connections 35' to the clip 45 on the frame of the cage A and 20 to the clip 39 on the arm 37, of the bar 15. The attendant on the train connects the mail bag 24 by the flexible connections 24' to the clip 40 on the arm 38 and to the clip 46 on the upper frame of the cage B. As the 25 train moves by the station the cage B passes under the cage A. The front bars 16 and 17 of the station cage A engage the flexible connections 24' of the mail bag 24 and thereby disconnect the mail bag 24 from the cage B 30 and the arm 38. Simultaneously with this disconnection of the mail bag 24 from its mounting, the flexible connections 35' of the bag 35 are engaged by the upper and lower bars 16 and 17 of the cage B and the 35 bag 35 disconnected from the clips 45 and 29. The two bags 24 and 35 being thus disconnected simultaneously as the train passes the station, the bags 24 and 35 are shot or snapp'd into the cages A and B. The chain 40 netting of the cages receives the shock, if any, and, owing to the inclined backs of the cages A and B, the bag 24 may be thrown back of the platform 10 while the bag 35 may slide directly into the train through the 45 opening 25. Ordinarily, the impact of the bags against the inclined backs of the cages will cause the bags to drop on the bottoms

of the cages. The attendants may then swing the cages to inoperative position.

It will thus be seen that I yieldably support the catching devices shown to reduce the impact incident to shock and that by virtue of the chain mesh or other material forming the body of the cages, the bodies of the cages are yieldable and thereby aid in reducing shock incident to impact when the mail bags are taken from the crane mechanisms. The chain mesh may be easily repaired and, if desired, in the event of wear it is obvious that fabric or cloth which is also yieldable, may be substituted for the chain mesh material or the like.

What is claimed is:

1. In a mail bag catching device, a support, a rotatable bar mounted thereon, means for retaining said bar against rotation, a U-shaped frame secured at its terminals to said bar constituting with the bar a rectangular frame, a mail bag receiving cage having a rectangular mouth secured to said rectangular frame, the inner side of the mail bag receiving cage being disposed parallel with the support, and the outer side thereof sloping from the support to the outer side of the rectangular frame, and resilient means attached to the inner end of the mail bag receiving cage and to the support.

2. In a mail bag catching device, a support, a rotatable bar mounted upon said support, means for retaining said bar against rotation, a U-shaped frame secured at its terminals to said bar and constituting with the bar a rectangular frame, a mail bag receiving cage attached at its open end to said rectangular frame, and resilient means for securing the inner end of the cage to the support.

In testimony whereof I have affixed my signature in presence of two witnesses.

WILLIAM J. HERBST.
